US00D983751S

(12) **United States Design Patent** (10) **Patent No.:** **US D983,751 S**
(45) **Date of Patent:** **** Apr. 18, 2023**

(54) **MEDICAL DEVICE CONNECTOR**

(71) Applicant: **Physio-Control, Inc.**, Redmond, WA (US)

(72) Inventors: **Christopher Alviar**, Redmond, WA (US); **Ryan Bowman**, Redmond, WA (US); **Neal Clark**, Redmond, WA (US); **Zack Pahlman**, Redmond, WA (US); **Jeremy Wong**, Redmond, WA (US); **John Depillo**, Redmond, WA (US)

(73) Assignee: **Physio-Control, Inc.**, Redmond, WA (US)

(**) Term: **15 Years**

(21) Appl. No.: **29/708,183**

(22) Filed: **Oct. 3, 2019**

(51) **LOC (14) Cl.** **13-03**

CLAIM

The ornamental design for a medical device connector, as shown and described.

DESCRIPTION

FIG. 1 is a top perspective view of a medical device connector;

FIG. 2 is an enlarged perspective view of the medical device connector shown in FIG. 1;

FIG. 3 is a top view thereof;

FIG. 4 is a front side view thereof;

FIG. 5 is a back view thereof; and,

FIG. 6 is a side view thereof.

The dashed-lines represent the remainder of the article and do not form part of the claimed design, are directed to environment, and represent unclaimed subject matter.

1 Claim, 4 Drawing Sheets
